(57) **CLAIM**

We claim the ornamental design for a shaver and charger assembly, as shown and described.

DESCRIPTION

FIG. 1 is a top perspective view of a design for a shaver and charger assembly according to the present invention;

FIG. 2 is a front view thereof;

FIG. 3 is the back view thereof;

FIG. 4 is a left view thereof;

FIG. 5 is a right view thereof;

FIG. 6 is a top view thereof; and,

FIG. 7 is a bottom view thereof.

The broken lines shown in the drawings depict portions of the shaver and charger assembly and form no part of the claimed design.
